THORSTEN ZWEIGBERGK, OF LONDON, ENGLAND.

CIRCUIT MAKING AND BREAKING DEVICE.

Application filed December 20, 1923, Serial No. 681,719, and in Great Britain December 27, 1922.

This invention is concerned with circuit making and breaking devices and the general object of my invention is directed to the provision of an electro-magnetically operated circuit breaker having an independently, mechanically operated mechanism adaptable for conjoint action with the electro-magnetic mechanism to close the circuit whereby a relatively strong force may be exerted to close the circuit breaker without necessitating the incorporation of heavy electro-magnetically operable parts and to thereby greatly increase the breaking characteristics of the device under electro-magnetic control.

A further object of my invention is the adaptation thereof in a specific form to an electric motor control system such as I disclose in my Patent No. 1,412,589 issued April 11, 1922.

Other objects of my invention will hereinafter be set forth in the following description which refers to the accompanying drawings illustrating an embodiment thereof adapted to an electric motor control system. The essential characteristics are summarized in the claims.

In the drawings, Fig. 1 is a side elevation of a circuit breaker mechanism embodying my invention; Fig. 2 is a plan view of the device shown in Fig. 1; Fig. 3 is a cross-sectional plan view taken substantially along the line 3—3 of Fig. 1; Fig. 4 comprises a diagrammatic illustration of a preferred adaptation of the circuit breaker device to an electric motor control system such as I have hereinbefore referred to.

My invention contemplates the combining of an electro-magnetically operated circuit breaker and a mechanically operated means for positively closing the circuit breaker, the devices being combined in such manner that a conjoint action thereof is necessary to close the circuit breaker contacts but both are separately effective in permitting an opening of the contacts.

In carrying out the objects of my invention, the electro-magnetic device and the mechanically operated means are preferably connected to a contact carrying member whereby either or both devices may be effective in moving the contact carrying member. A preferred form of this arrangement is shown in Fig. 1 wherein a fixed contact 10 may be mounted upon a base or rigid frame 11. A movable contact 12 is shown as being

pivotedly mounted upon a pair of depending arms 13 which may be pivotally mounted as indicated at 14 in any suitable manner upon insulated frame members 15. An iron clad solenoid magnet 16 is preferably mounted upon the frame portion 11^a to be disposed above the arms 13 whereby a suitable link mechanism may be provided to connect the armature 17 of the electro-magnet with the arms 13. This link mechanism preferably includes a pair of toggle arms 18 and 19 which are connected to an extension arm 20 of the armature 17 by intermediate links 21.

The toggle arms 18 and 19 also serve to connect the mechanical operating means with the arms 13 and this mechanical means in the present adaptation of my invention may comprise a cam 25 mounted upon the shaft 26 of a main motor resistance controller drum to be hereinafter referred to. The cam 25 has formed, about the periphery thereof, a recess 26' into which a cam follower or roller 27 may ride. The roller 27 may be carried on a pair of lever members 28 which may be pivotally mounted, as indicated at 29, on downward extensions 30 of the frame members 15. The upper ends of the lever members 28 are pivotally connected at 31 to the toggle arm 19.

The contacts 10 and 12 are preferably separated by a powerful spring action which may be obtained by a spring 35 suitably mounted upon a plunger 36 supported by a bracket 37 secured to the frame of the device. One end of the plunger 36 may be free while the other end engages an extension of a contact carrying arm 38 carried by the large arms 13. The swinging movement of the arm 38 relative to its supporting arms 13 may be sufficiently limited whereby during the first part of the closing action of the device, the non-corroding portion 12^a of the contact 12 will first contact with the non-corroding portion 10^a of the rigidly mounted contact 10.

In adapting my invention to a motor control system, I provide an auxiliary switch mechanism which may be incorporated in the present mechanism in such manner as to be operated by the solenoid armature 17. As shown in Fig. 1, a plunger 40 is slidably mounted to extend through the core 41 of the solenoid whereby one end thereof may bear against the armature 17 while the other end may act upon a contact carrying mem-

- ber 42 and may be pivotally mounted as indicated at 43 on an extension 44 of the solenoid housing 16. The member 42 carries a contact block 45 having fixed contacts 46 and 47 mounted thereon to cooperate with a resilient switch plate 48. The switch plate 48 together with others to be described may be supported by an insulated bracket construction 49 carried by the extension 44.
- 16 A compression spring 50 may react between the solenoid housing and a lower end 42^a of the member 42 to normally maintain the contact switch plate 48 connected with the contact 46 when the solenoid is being energized. This spring likewise maintains the member 42 in engagement with the rod 40. The ends of the rod 40 thus, under all conditions, are pressed between the armature 17 and the contact carrying member 42.
- 20 If desired, an interlocking feature to operate between the auxiliary circuit breaker mechanism and the main circuit breaker mechanism may be provided by extending the switch member 42 downwardly to engage and cooperate with an extension 13^a of the arm 13. An advantage of such an arrangement will be hereinafter set forth.
- 25 A circuit breaker device such as I herein disclose, in its general principle of operation may be adapted to many uses, but the particular embodiment specifically illustrated and described is adaptable for breaking the main motor line in an electric controlling system wherein the main motor current is controlled through a motor driven controller, the auxiliary motor driving this controller being regulated in its starting and stopping action by a manually operated master controller.
- 30 Such a system is diagrammatically represented in Fig. 4 which also includes a diagrammatic representation of the movable elements of my circuit breaker device in their cooperative relation to the system. It will be noted that in this diagram, the switch member, in addition to contacts 46 and 47 carries a ground contact 55 and additional contacts 56, 57, 58 and 59 which cooperate with suitable resilient contacts mounted similarly to the member 48. A master controller "M" shown as being mounted upon the shaft 26 which carries the cam 25 of the mechanical circuit breaker operating means. The master controller is shown as being provided with seven controlling or contacting positions including the off positions as indicated by the dot and dash lines, two of which 60 and 61 are shown. The main motor controller drum "M" is usually rotated to a predetermined extent by a worm wheel 64 mounted upon the shaft 26 and a worm 65 mounted upon an auxiliary motor shaft 66. The action of the auxiliary motor "X" is predetermined by the manually operated master controller indicated at "T".

Fixed contacts "C" cooperate with the movable segment contacts on the master controller "T". The positions of these contacts are indicated by dot and dash lines. Two of the segment contacts 68 and 69 are shown in full lines. These contacts cooperate with the fixed contacts 70 and 71 respectively. 70

The establishing of various circuits by the master controller determines the direction of rotation of the armature of the auxiliary motor "X" whereby the shaft 26 is driven forwardly or backwardly through the worm and gear and the field windings 80 of the auxiliary motor and the windings of the armature thereof are connected in the circuit to be under the control of the master controller. Thus when the drum of the main controller is in the off position as shown in Fig. 2, the fixed contacts 60 and 61 (one of which is grounded) are bridged by moving contact segment 81 on the main motor controller drum for a purpose to be hereinafter described. 75 80 85

When the operator shifts the master controller "T" to its first position, segment contacts 68 and 69 are brought into engagement with contact 71 and current from an auxiliary source passes through these contacts to the solenoid line 90. Solenoid coil "S" is thus energized due to the grounding of the solenoid line 91 through contacts 60, 61 and 81 respectively and which normally connect the line 91 to ground 92. The armature 17 is consequently attracted by the solenoid coil. The solenoid extension 20 moves 95 100 the swinging link 21 in a downward direction thus bringing the toggle arms 18 and 19 to a position not quite in alignment. The arms 13 are thus swung to the left, bringing the main motor line contact 12 of 105 the circuit breaker into juxtaposition with the fixed contact 10 of the circuit breaker. This action of the solenoid through the link connections therefore overcomes part of the force of the spring 35. The solenoid armature, by reason of its action upon the plunger 40, reacts upon the switch member 42 thus bringing the contacts 58, 47 and 48 into circuit closing relation and the line 94 and 95, connected therewith, establishes 110 115 energization of the auxiliary motor, the current being grounded through contacts 56 and 55 to ground 97. The auxiliary motor thus rotates the cam shaft 26 to bring the contact segments on the main motor controller drum to first position thus establishing a current supply to the main motors. At this point, the relationship of the contacts between the master controller "T" and the main motor controller "M" is such that the winding of a relay switch solenoid indicated at "R" is deenergized, the relay drops and short circuits the auxiliary motor armature lines 94 and 95, thus stopping the auxiliary motor. 120 125 130

It will be seen that by reason of this first movement of the controller drum shaft 26, the cam 25 is rotated sufficiently to advance the roller 27 out of the recess of the cam and this action causes a rocking movement of circuit breaker arms 28 and the arms 28 react upon the arms 13 through the toggle members 18 and 19 to positively and forcefully position the movable main motor line contact 12 upon the contact 10. The contacts 10 and 12 thus close a circuit between the source of the main current and the main motors, which current passes through appropriate resistances controlled by cams (not shown) on the shaft 26 and the main motors are consequently started with the proper supply of current.

It should be noted that when the main controller drum advanced to its first controlling position, the solenoid circuit 91 is opened by reason of the contact segment 81 being shifted out of engagement with contact 60 and 61 and to maintain a continued energization of the magnet, I provide a connection on the switch member 42 for maintaining the grounded condition of the solenoid line. This connection is represented by a contact 55 grounded at 97, which contact is shifted into engagement with the resilient contact 56, the latter being connected in the solenoid line by the line 98.

Further shifting of the master controller "T" to successive positions establishes the auxiliary motor armature circuit in the manner described to cause the same to energize the armature of the auxiliary motor whereby the latter advances the main controller drum to corresponding successive positions, each position corresponding to further resistance being cut out of the main motor circuit by switches, (not shown) actuated by cams carried on the drum shaft 26. The relay circuit will be energized and deenergized in the manner described for each step.

When it is desired to deenergize the main motors, the master controller "T" may be shifted to its off-position, thus cutting off the supply of current to the solenoid coil. When the solenoid coil is thus deenergized, the armature will drop until arrested in its movement by the bumper spring 9 and the toggle links will thereupon collapse under the influence of spring 35, thus permitting the contacts to be sprung apart and the main motor current is thereby interrupted. This action takes place regardless of the relation of the cam follower 27 to the notch 28 of the cam 25.

Simultaneously with the release of the armature 17, the switch member 42 is shifted inwardly toward the solenoid by reason of the action of the spring 50 and a current is thereby established in the field windings 80 of the auxiliary motor through the line 98 by reason of the contacts 58, 47 and 57

through lines 94, 95 to 48, 46 and ground 96 establishing a grounded connection of this line which is always connected to a source of current. The auxiliary armature is thus driven in an opposite direction and the drum shaft 26 rotated in a reverse direction to bring the cam recess 28 into proper starting relation to the cam follower 27. This reverse rotation of the drum shaft 26 is continued until the drum is returned to initial off-position whence the auxiliary field circuit is interrupted by disengagement of contacts, (not shown) which are relatively movable consequent to this rotation of the drum shaft.

It should here be noted that the operator cannot energize the solenoid magnet by any subsequent shifting of the master controller to a running position until the auxiliary motor has completed its reverse rotation to bring the main motor controller drum back to its off-position whereby the solenoid circuit is completed by contacts 60, 61 and 81.

The purpose of an interlocking mechanism between the two switch devices of the circuit breaker will now be set forth. It sometimes occurs that when a circuit breaker operating in a system such as I herein disclose is subjected to an unusually heavy passage of current through the contacts, thus causing burning or arcing thereof and under exceptional circumstances a heavy rush of current may cause the welding together of the contacts thus rendering ineffective the responsive characteristics of the circuit breaker.

To meet such a contingency two of the circuit breakers may be arranged side by side for joint cooperation in series and the cams for operating these two mechanisms may be carried, for instance, by the drum shaft 26 and may be so associated that one breaker closes slightly before the other. The damaging effect of an unusual rush of current would then be present at the contacts of only one of the circuit breakers thus leaving the other in operative condition to interrupt the circuit at the desired time. It is desirable, however, that when two breakers are thus used that either one be prevented from reclosing if the other were to have the contacts fused together. The foregoing conditions may be met, however, by the provision of only one auxiliary switch mechanism, and the contact carrying member 42 thereof may be provided with an extension in the nature of a depending arm 42^b to engage and interlock on a projection 13^b formed on the extension 13^a of the contact carrying arm 13. The extension 42^b consequently cannot pass this projection 13^b in the event the contacts are fused together and the switch member 42 is thus prevented in its movement. Shifting of the contacts carried thereby, whereby the auxiliary motor is caused to rotate in a reverse direction to bring the main motor con-

125
130

troller drum to the off-position is prevented and until this is effected the breaker which is arranged to close slightly before the other breaker is closed cannot be closed again due 5 to the unalignment of the recess of its cam with its cam follower.

From the foregoing description of my invention it will be readily apparent that the solenoid and parts actuated thereby may be 10 comparatively light in construction due to the fact that I obtain a positive relatively powerful closing of the contacts of the circuit breaker by mechanical means. I therefore obtain a very rapid breaking action or 15 parting action of the contacts by the use of a spring member which may be much lighter than would otherwise be necessary.

It will also be apparent that if desired the 20 circuit breaker contacts could be opened and closed by the mechanical action of the cam and connecting levers acting on the movable contact arms when the armature of the solenoid is in its attracted position. It would 25 also be possible to close the circuit breaker contacts as well as to open them by energizing the solenoid magnet to set the contacts against the full force of the spring when the mechanically operated parts of the 30 device are in such condition that the roller or follower is out of the cam recess. Such a closing action, however, would necessitate the use of a more powerful magnet and a heavier construction of all the associated parts, thus depreciating the rapid breaking 35 characteristics that I otherwise obtain when the final closing is effected mechanically.

It is to be further understood that the specific form of construction herein set forth, is shown as being particularly adapted 40 to electric motor control systems merely for the purpose of illustrating the adaptability of my invention to practical uses and that the scope of the invention is not to be understood as being confined to the details herein 45 described.

I claim:

1. In a circuit making and breaking device, the combination of a pair of contacts, means for effecting a relative movement between the contacts and electromagnetically actuated mechanism acting on said means to move one of the contacts and a mechanically operated means acting through the electromagnetically actuated means to supplement the movement of the contact and completely close the contacts whereby the electromagnetically actuated means moves the contact during one time interval and the mechanical means completes the movement in another time interval.

2. A circuit breaker of the character described, having in combination a pair of relatively movable contacts, electromagnetic means for effecting said relative movement, said electromagnetic means including a sole-

noid, a casing therefor and a plunger extending therethrough, a mechanically operated means for effecting said movement, a mechanism operatively connecting both the said means whereby either may be effected in 70 causing said relative movement of the contacts, an auxiliary reversing switch mechanism pivotally mounted on the casing, and resiliently urged into contact with the plunger and adapted to be actuated by the 75 electromagnetic means, and an interlocking device between the auxiliary switch mechanism and the contact moving mechanism.

3. A circuit breaker of the character described, having in combination a pair of relatively movable contacts, electro-magnetic means for effecting said relative movement and mechanically operated means for effecting said movement, a mechanism operatively connecting both of said means whereby 85 either may be effective in causing said relative movement of the contacts an auxiliary switch mechanism actuated by the electro-magnetically operated means, and an interlocking device between the auxiliary switch 90 mechanism and the contact moving mechanism.

4. In a circuit breaker the combination of a pair of separable contacts, a mechanical means for closing the contacts, electro-magnetically operated means for effecting a relative movement of the contacts, an electro-magnet therefore, a second pair of relatively movable contacts, means actuated by the electromagnetically operated means for causing movement of said last named contacts, and means for preventing relative movement of the last named contacts when the first named contacts fail to separate upon the de-energization of the electro-magnet.

5. In a circuit breaker the combination of a pair of separable contacts, a mechanical means for closing the supports, electro-magnetically operated means for effecting a relative movement of the contacts, a second pair 110 of relatively movable contacts, a shiftable support therefor, means actuated by the electro-magnetically operated means for causing movement of the support and means for interlocking the support and the mechanically 115 operated means in the event the contacts are fused together.

6. In a circuit breaker the combination of a pair of separable contacts, electro-magnetically operated means for effecting a relative movement of the contacts, an electro-magnet therefore, a second pair of relatively movable contacts and means for preventing movement of the contacts when said first named contacts fail to separate upon the de-energization of the electromagnet.

7. In a circuit breaker, the combination of a pair of relatively movable contacts, an electro-magnetically operated means for effecting said movement, an electro-magnet 120

therefor, a mechanically operative means also effective to cause said movement, said mechanical means being ineffective to close the contacts precedent to actuation of the 5 electro-magnetically operated means, an auxiliary switch mechanism adapted to be actuated by the electro-magnetically operated means prior to the closing of the relatively movable contacts by the mechanical 10 means and an interlocking device adapted to prevent movement of the switch mechanism in the event said contacts fail to separate consequent to the deenergization of the magnet.

15 8. In a circuit making and breaking device, the combination of relatively movable contacts, movable means supporting one of the contacts, electro-magnetic means for actuating said movable means, a toggle arranged 20 whereby the electro-magnetically operated members may effect a preliminary closing movement of said contact supporting means and mechanically operated means acting on the toggle to effect a final positive 25 closing movement of the contacts.

9. In a circuit making and breaking device, the combination of relatively movable contacts, movable means supporting one of the contacts, electro-magnetically operated 30 means for actuating the movable supporting means including a toggle arranged whereby the electro-magnetically operated means may effect a preliminary closing movement of said contact supporting members and mechanically operated means acting on the 35 toggle to effect a final positive closing movement of the contacts, the association of the two devices being such that the electro-magnetically operated means may be actuated to permit releasing of the toggle independently 40 of any movement of the mechanically operated means.

10. In a circuit breaker device the combination of a pair of relatively movable contacts, electro-magnetically operated means 45 for effecting a closing movement of the contacts, a resilient means opposing said movement and adapted to normally maintain the contacts separated, the electro-magnetically 50 operated means being effective to overcome only a part of the opposition of said resilient means and a mechanically operated means for completing the closing movement of the contacts by a positive application of force in 55 opposition to said resilient means.

11. In a circuit breaker device the combination of a pair of relatively movable contacts, electro-magnetically operated means 60 for effecting a partial closing movement of the contacts, a resilient means opposing said movement and adapted to normally maintain the contacts separated, and a mechanically operated means for completing the

closing movement of the contacts by a positive application of force in opposition to 65 said resilient means.

12. In a circuit breaker device the combination of a pair of relatively movable contacts, electro-magnetically operated means for effecting a closing movement of the contacts, resilient means opposing said movement and adapted to normally maintain the contacts separated, a mechanically operated means for completing the closing movement of the contacts by a positive application of 70 force in opposition to said resilient means, an auxiliary switch mechanism operated by the electro-magnetically operated means and a locking mechanism for preventing actuation of the switch mechanism when said 75 resilient means fails to separate the contacts.

13. In a circuit making and breaking device, the combination with a pair of relatively movable contacts of electro-magnetically operated means for effecting a partial 80 closing movement of the contacts, an electro-magnet therefor, a mechanically operated means for completing said closing movement, and auxiliary switch mechanism operated by one of said means, said auxiliary 85 switch mechanism including an interlocking device whereby its operation is prevented upon failure of the contacts to separate when the electro-magnet is deenergized.

14. In a circuit making and breaking device, the combination with a pair of relatively movable contacts of an electro-magnetically operated means for effecting a partial 90 closing movement of the contacts, a mechanically operated means for completing 100 said closing movement, an auxiliary switch mechanism operated by one of said means, said auxiliary switch mechanism including an interlocking device adapted to engage the mechanically operated means to prevent operation of the switch mechanism upon failure of the contacts to separate.

15. In a circuit making and breaking device, the combination with a pair of relatively movable contacts of an electro-magnetically operated means for effecting a partial 110 closing movement of the contacts, one of the contacts being mounted on a movable member, a mechanically operated means for completing said closing movement, an auxiliary 115 switch mechanism operated by the electro-magnetically operated means, said auxiliary switch mechanism including a locking device engaging the contact carrying member whereby its operation is prevented upon failure of the contacts to separate when the electro-magnetically operated means is rendered inactive.

In testimony whereof, I hereunto affix my signature.

THORSTEN ZWEIGBERGK.
